PUMP

James H. Fitzgerald, Westfield, N. J.

Application October 7, 1944, Serial No. 557,650

21 Claims. (Cl. 103—166.5)

This invention relates to pumps and has special reference to a pump of the force delivery type particularly adapted for the handling of concrete and other semi-fluid materials.

One important object of the invention is to improve the general construction of pumps of this character so that they may operate smoothly and deliver the material in a uniform state throughout the operation of the pump.

A second important object of the invention is to provide in a device of this kind having a hopper, means for cutting off supply from the hopper during the expulsion stroke of the pump, such means being of novel character.

A third important object of the invention is to provide a novel form of piston for the pump wherein the piston is so shaped and arranged as to form a cut-off for material delivered to the pump cylinder.

A fourth important object of the invention is to provide novel valve means operating to admit air between the piston and the material being delivered during the retraction stroke of such piston.

A fifth important object of the invention is to provide means for the automatic operation of the various parts of the invention so that control may be had from a single operating station.

With the above and other objects in view as will hereinafter be apparent, the invention consists in general of certain novel features of construction and combinations of parts hereinafter fully described, illustrated in the accompanying drawings and particularly claimed.

In the drawings:

Figure 1 is a side elevation, partially broken away, showing the invention.

Figure 2 is a longitudinal section to an enlarged scale, the section being taken on the axis of the pump cylinder.

Figure 3 is a view, partly in section and partly in elevation, on line 3—3 of Figure 1.

Figure 4 is an enlarged detail section on line 4—4 of Figure 1.

Figure 5 is a view similar to Figure 4 but showing the parts in a position different from that shown in Figure 4.

Figure 6 is an enlarged section on line 6—6 of Figure 3.

Figure 7 is a section on line 7—7 of Figure 2.

Figure 8 is a vertical axial section showing a modified form of valve for controlling the flow of material from the hopper.

Figure 9 is a plan view of the valve means shown in Figure 8.

Figure 10 is an enlarged detail section on line 10—10 of Figure 9.

Figure 11 is a fragmentary view showing a section of the pump in a modified form.

Figure 12 is a section on line 12—12 of Figure 11.

In the embodiment of the invention as herein shown there is disclosed a base 10 which may consist of a pair of structural elements such as I-beams, channels or the like. On one end of this base is mounted an operating cylinder 11 having the usual piston (not shown) and piston rod 12. On the base 10 is a special valve 13 having an operating handle 14. This valve may be of any desired construction, no claim being made to particular construction thereof. The valve receives operating fluid such as steam, compressed air, or liquid under pressure through an inlet pipe 15 and exhausts the operating fluid through an exhaust pipe 16. The ends of the cylinder 11 are connected to this valve 13 by means of pipes 17. When the operating handle 14 is in one position the valve will connect the inlet pipe 15 to one end of the cylinder and the exhaust pipe 16 to the other end of the cylinder in another position of the handle 14 these connections will be reversed.

In the form of the invention shown in Figures 1 to 7, the material to be pumped is loaded into a hopper 18 and beneath this hopper is a screw conveyor 19 operated by any preferred means, such means being not deemed necessary here to be shown. Depending from the delivery end of the screw conveyor is a delivery spout 20 which is connected to the upper end of a valve box 21. Extending diagonally within this valve

box 21 is a diaphragm 22 having an opening 23 therein. Journalled in one side of the valve box is a perpendicular stub shaft 24. A plate 25 rests against the underside of the diaphragm 22 and is provided with a projecting boss 26 which is keyed to the lower end of the shaft 24 within the valve box. Thus this plate 25 may be rotated by the stub-shaft 24 to close or open the opening 23.

On the upper end of stub-shaft 24 is keyed or otherwise secured a rock arm 27. Fixed to the underside of the conveyor 19 is a bracket 28 having a pair of ears 29 which carry a pivot pin 30. At 31 is an operating cylinder having the usual piston (not shown) and piston rod 32. The rod 32 is pivoted by a pin 33 to the free end of the rock arm 27. From the cylinder 31 pipes 34 lead to the valve 13. This valve is so ported that when the cylinder 11 is connected to have its piston rod 12 protruded the piston rod 32 will be retracted and the delivery opening 23 will be opened. Also when the piston rod 12 is retracted

40 At 31 is an operating cylinder having the usual piston (not shown) and piston rod 32. The rod 32 is pivoted by a pin 33 to the free end of the rock arm 27. From the cylinder 31 pipes 34 lead to the valve 13. This valve is so ported that when the cylinder 11 is connected to have its piston rod 12 protruded the piston rod 32 will be retracted and the delivery opening 23 will be opened. Also when the piston rod 12 is retracted

45 At 31 is an operating cylinder having the usual piston (not shown) and piston rod 32. The rod 32 is pivoted by a pin 33 to the free end of the rock arm 27. From the cylinder 31 pipes 34 lead to the valve 13. This valve is so ported that when the cylinder 11 is connected to have its piston rod 12 protruded the piston rod 32 will be retracted and the delivery opening 23 will be opened. Also when the piston rod 12 is retracted

50 At 31 is an operating cylinder having the usual piston (not shown) and piston rod 32. The rod 32 is pivoted by a pin 33 to the free end of the rock arm 27. From the cylinder 31 pipes 34 lead to the valve 13. This valve is so ported that when the cylinder 11 is connected to have its piston rod 12 protruded the piston rod 32 will be retracted and the delivery opening 23 will be opened. Also when the piston rod 12 is retracted

the rod 32 will be protruded and the opening 23 will be closed.

The valve box 21 opens into the top of a pump cylinder 35 through an inlet branch 36.

The pump cylinder 35 is open at both ends and within this cylinder is a hollow piston 37 which fits closely in the cylinder. This hollow piston is closed at its forward end by a disc or head 38 but extending forwardly from this head the piston is provided at its upper part with a segmental extension 39 beveled at its forward edge as at 40. This segmental extension is of sufficient arcuate form to span the lower end of the inlet branch 36. A piston rod 41 connects the piston 37 to the piston rod 12 as at 42.

As shown in Figure 2, the piston is illustrated in the extreme delivery position in full lines and at the extreme retracted position in dotted lines. Now it will be obvious that if a rod of semi-fluid material such as concrete rests against the disc 38 and an attempt is made to retract the piston 37 there will be a tendency to establish a vacuum between the material just pushed forwardly and the disc or head 38. In order to prevent such tendency with consequent retraction of a portion of the load just pushed forwardly novel air inlet means are provided. To this end the lower part of the cylinder 35 just forwardly of the extreme forward position of the head 38 is slotted and in this slot works a plate 43 having its upper edge concavely arcuate so that when the plate is retracted to the fullest extent of its movement this arcuate upper edge 44 forms a continuation of the inner surface of the cylinder 35. On the side of this plate opposite the piston 37 is a groove 45 which is of such vertical extent that the groove lies entirely exterior of the cylinder 35 when the plate 43 is retracted but upon the plate being raised to its furthest extent the groove 45 will straddle the lower part of the cylinder wall and thus afford communication between the cylinder forward of the head 38 and the outer air. By this means air will be admitted in front of the cylinder 35 during retraction of the piston 37 and there will be no tendency to form a vacuum at this point.

In order to effect this operation automatically the cylinder 35 has depending guides 46 between which the plate 43 is guided. An operating cylinder 47 lies below the plate 43, the cylinder being provided with the usual piston (not shown) and piston rod 48 which latter is connected to the plate 43 as at 49. The cylinder 47 is connected to the valve 13 by means of pipes 50 and this valve is so ported that when the piston rod 12 is retracted the piston rod 48 will be protruded and when the piston rod 12 is protruded the piston rod 48 will be retracted. It will now be observed that one position of the handle 14 will effect simultaneous opening of the valve 25, dropping of the plate 43 and forward movement of the piston 37 while the other position of the handle 14 will close the valve 25, draw the piston 37 backwardly and raise the plate 43. Obviously, the arrangement of the valve must be such that the plate 43 will rise prior to backward movement of the piston 37.

In the form of the invention shown in Figures 8, 9 and 10 the hopper 51 is of inverted frusto-conical form and has at its lower end a neck 52 leading to the intake portion 36 of the cylinder 35. At the junction of the neck 52 with the hopper 51 there is fixed to the hopper a frusto-cylinder spreader plate 53 having therein a pair of openings 54. At the upper end of the

plate 53 there is provided a ball race 55 carrying ball 56 and on the ball rests a ball race 57 from which projects downwardly and outwardly a pair of segmental conical valve members 58 which in one position will close the openings 54 while in a second position they will keep these openings open. The upper ball race 57 is fixed on the lower end of a shaft 59 and this shaft is operated in the same manner as the shaft 24, the operating connection not being deemed necessary here to be shown.

In the form of the invention shown in Figures 11 and 12, the hopper 60 is of ordinary conical form and delivers to a pump intake portion 61 which opens into the upper side of a cylinder having forward end portion 62 and a rear end portion 63, these end portions being connected at opposite ends of a washing cell 64 having its central portion of somewhat greater diameter than the diameter of the cylinder portions 62 and 63. A water supply pipe 65 leads to the cell 64 and a water drain pipe 66 leads therefrom. The cylinder 67 differs from that shown in Figure 2 since it has no forwardly projecting portion such as shown at 39. However, it is operated in the same manner by the piston rod 41. The pump intake 61 is formed with a forwardly extending pocket 68 which is normally closed off from the remainder of the intake 61 by means of a flexible apron 69 of rubber or other suitable material, this apron having a substantial semi-circular lower edge which fits around the piston 67 as shown in Figure 12. The purpose of this apron is to prevent jamming of the pump when pumping such material as concrete by a stone engaging between the upper forward edge of the piston 67 and the wall of the intake 61. The pocket 68 is large enough to accommodate any such stone and under these conditions if such a stone were to fall into position to be engaged by the upper forward edge of the piston 67 it would simply push the apron 69 into the pocket 68 and be held in the pocket during the forward movement of the piston, dropping back into the cylinder portion 62 when the piston is retracted.

In this form of the invention the plate 43 has been shown as operating from the upper side of the cylinder but the operation will be the same as the form shown in Figure 2.

What is claimed is:

1. In a pump, a cylinder having a lateral intake opening and an end discharge opening, a piston reciprocable across said opening between expulsion and admission positions, and relief valve means for admitting air to the cylinder forwardly of the expulsion end of the piston stroke.

2. In a pump, a cylinder having a lateral intake opening and an end discharge opening, a piston reciprocable across said opening between expulsion and admission positions, and relief valve means for admitting air to the cylinder forwardly of the expulsion end of the piston stroke, said relief valve means including a plate extending transversely of the cylinder and having an air admission groove on the side opposite the piston.

3. In a pump, a cylinder having a lateral intake opening and an end discharge opening, a piston reciprocable across said opening between expulsion and admission positions, relief valve means for admitting air to the cylinder forwardly of the expulsion end of the piston stroke, and operating means effecting reciprocation of said piston and operation of said relief valve means in timed relation with the relief valve open

expulsion and admission positions, said cylinder having a material receiving relief chamber forwardly of said inlet opening, a flexible curtain between the inlet opening and relief chamber, and relief valve means for admitting air to the cylinder forwardly of the expulsion end of the piston stroke.

16. In a pump, a cylinder having a lateral intake opening and an end discharge opening, a piston reciprocable across said opening between expulsion and admission positions, said cylinder having a material receiving relief chamber forwardly of said inlet opening, a flexible curtain between the inlet opening and relief chamber, and relief valve means for admitting air to the cylinder forwardly of the expulsion end of the piston stroke, said relief valve means including a plate extending transversely of the cylinder and having an air admission groove on the side opposite the piston.

17. In a pump, a cylinder having a lateral intake opening and an end discharge opening, a piston reciprocable across said opening between expulsion and admission positions, said cylinder having a material receiving relief chamber forwardly of said inlet opening, a flexible curtain between the inlet opening and relief chamber, relief valve means for admitting air to the cylinder forwardly of the expulsion end of the piston stroke, and operating means effecting reciprocation of said piston and operation of said relief valve means in timed relation with the relief valve open during admission stroke and closed during expulsion stroke of said piston.

18. In a pump, a cylinder having a lateral intake opening and an end discharge opening, a piston reciprocable across said opening between expulsion and admission positions, said cylinder having a material receiving relief chamber forwardly of said inlet opening, a flexible curtain

between the inlet opening and relief chamber, relief valve means for admitting air to the cylinder forwardly of the expulsion end of the piston stroke, said relief valve means including a plate extending transversely of the cylinder and having an air admission groove on the side opposite the piston, and operating means effecting reciprocation of said piston and operation of said relief valve means in timed relation with the relief valve open during admission stroke and closed during expulsion stroke of said piston.

19. In a pump, a cylinder having a lateral intake opening and an end discharge opening, a piston reciprocable across said opening between expulsion and admission positions, and relief valve means for admitting air to the cylinder forwardly of the expulsion end of the piston stroke, said relief valve means including a plate extending transversely of the cylinder and having an air admission groove on one side thereof.

20. A pump as set forth in claim 1, wherein the relief valve means includes an element adapted to enter the cylinder and constructed for the admission of external air to the cylinder upon entry of the element into the cylinder.

21. In a pump, a cylinder having a lateral intake opening and an end discharge opening, a piston reciprocable across said opening between expulsion and admission positions, and relief valve means for admitting air to the cylinder forwardly of the expulsion end of the piston stroke, said relief valve means including a plate extending transversely of the cylinder and having an air admission groove on one side thereof, said cylinder having an opening therein for the passage of said element and said element being normally disposed in said opening to present one end thereof as a part of the cylinder wall.

JAMES H. FITZGERALD.
